FLUID MEASURING AND DISPENSING
DEVICE

John T. Arnold, Camden, Ark.

Application June 14, 1950, Serial No. 168,058

4 Claims. (Cl. 222-417)

1

The present invention relates to devices for measuring and dispensing a predetermined quantity of fluid.

An important object is to provide a receptacle or device which can be conveniently detachably connected to a fluid container, such as a medicine bottle or the like, and which is provided with means so that when the receptacle is connected to the container and the latter is in an upright position and then reversed or turned upside down, a measured or predetermined quantity of the fluid or liquid will flow from the container into the receptacle. Conversely, when the container is returned to its upright position the fluid will flow back into the container, while a predetermined quantity of the fluid is retained in the receptacle so that it may be poured into a glass or the like when the receptacle is disconnected from the container.

Other objects and advantages of the invention will become apparent from the following description when taken in conjunction with the accompanying claims and drawings.

Referring to the drawings in which is shown a preferred embodiment of the invention:

Figure 1 is a side view of a vessel or bottle in an upright position and showing the improved receptacle connected thereto.

Figure 2 is an enlarged detailed sectional view with the parts in their filling position.

Figure 3 is a sectional view similar to Figure 2 with the container in its upright position and showing the measured liquid ready to be dispensed.

Figure 4 is a detailed sectional view showing the receptacle detached from the bottle or container and in its inclined discharging position.

Figure 5 is a plan view of Figure 1.

Figure 6 is a sectional view taken substantially along the line 6-6 of Figure 5, and

Figure 7 is a sectional view taken substantially along the line 7-7 of Figure 6.

Referring to the drawings, 10 indicates a suitable fluid container such as a medicine bottle or the like which may be provided with an externally threaded neck 11 for normally receiving a cap or closure not shown. In order that measured quantities of the fluid or liquid can be removed from the bottle without waste and in predetermined quantities, there is associated with the bottle a combined measuring and dispensing device or receptacle 12 which may be formed of glass, plastic or other suitable material and may vary in size and shape in accordance with its particular use. Preferably, the body of the receptacle 12 is cylindrical so as to provide interiorly thereof a fluid chamber 13 that is closed at one end by a base 14 and is provided at its opposite end with a transverse annular member 15 which has extending outwardly and centrally therefrom a reduced tubular end portion 16 having a central bore or

2

conduit 17 communicating with the chamber 13. The reduced portion 16 or neck is internally threaded adjacent its outer end as at 18 (Fig. 6) so as to be detachably connected to the complementary threads 11 on the container or bottle 10. Of course, any other suitable means may be provided for detachably connecting the dispenser to the container. In order to insure a water-tight seal when the parts are connected, a gasket 19 is preferably interposed between the lip of the neck 18 and an annular shoulder portion 20 in the wall of the bore 17 (Fig. 3).

Extending longitudinally within the chamber 13 and substantially centrally thereof is a partition or dam 21 which is connected in any suitable manner as at 22 to the inner wall of the transverse member 15 and to opposite walls of the chamber as at 22' (Fig. 7). It will be noted the partition projects across the inner end of the bore 17 of the neck 16. The outer free end of the partition 21 terminates short of the base 14 (Fig. 3) so that the partition 21 separates the chamber into a combined receiving and discharging compartment 23 and a measuring compartment 24 that communicate with each other

20 through the passage 25 formed by the free end of the partition 21 and the adjacent wall of the base or end 14. An overflowing member or tube 26 positioned in the measuring compartment 24 is suitably connected as at 27 (Fig. 6) to the inner wall of the transverse member 15 and may be integrally connected to the partition 21 so as to extend parallel therewith. The overflow member 26 has an axial restricted opening or passage 28

25 which communicates at one end with the bore 17 and its opposite end with the measuring chamber 24 at a point short of the free end of the partition (Fig. 3) so as to maintain the level of the fluid in the compartment uniform and allow the excess fluid to return to the bottle through the opening 28 when the bottle is in its upright position. The member 26 closes communication of the inner end of the measuring compartment with the bore or opening 17. The receiving and discharging compartment 23 communicates with the bore 17 through a relatively wide transverse opening 29 (Fig. 5) as contrasted to the restricted overflow opening 28.

50 In operation, assuming that the container or bottle 10 is filled with fluid which it is desired to use in uniform or measured quantities, the receptacle or vessel 12 when in an upright position, such as shown in Figure 1, is threadedly connected to the tubular portion 16 of the dispenser 12 so as to form a tight sealing engagement therewith through the gasket 19. The bottle 10 with the dispenser attached thereto is then turned upside down or reversed, thus causing a certain quantity of the fluid in the receptacle to flow into the surmounted container so as to completely fill the receiving and dis-

55

60

charging compartment 23 and to fill the measuring compartment up to a point approximately as indicated at 30 (Fig. 2). The inverted bottle 10 is then returned to its upright position allowing the excess fluid in the receiving compartment to be poured back into the bottle through the opening 29 and the bore 17. The fluid in the measuring compartment is retained or confined therein up to the level 31 of the overflow member (Fig. 3) and upon unscrewing the device 12 from the bottle, the liquid contents of the compartment 24 may be tilted (Fig. 4) and poured out into a glass or other receptacle. Thus, simple, efficient and positive means are provided for insuring an exact or uniform amount of liquid to be measured and dispensed from the device by the simple expedient of turning the bottle upside down and then returning to its upright position when the device 12 is connected thereto.

It will be manifest that the size of the measuring compartment 24 may be varied so as to measure and discharge predetermined quantities of fluid to insure accuracy of the amount of fluid dispensed and without waste and at a minimum expenditure of time and effort.

The form of the invention shown is merely illustrative of a preferred embodiment and such changes may be made as come within the scope of the following claims.

I claim:

1. A fluid measuring receptacle of the class described including a body having a chamber therein, said chamber being closed at one end by a base and having a transverse member at its opposite end provided with an outwardly extending tubular portion, said tubular portion having means for detachably connecting the device to a fluid container, a partition in said chamber separating the same into a receiving compartment and a measuring compartment, said partition engaging centrally the transverse member and the opposed sides of the body, said partition terminating short of the base to form a passage communicating said compartments with each other, and an overflow member in said measuring compartment having a longitudinal opening communicating at one end with said tubular portion and at its opposite end with the measuring chamber, said device when communicatively connected to a fluid container being reversible so as to discharge a portion of the fluid into the measuring chamber and when returned to its upright position returning the fluid in the receptacle through the receiving chamber and the overflow member to the container while retaining a predetermined quantity in the measuring chamber.

2. A fluid measuring receptacle of the class described including a body having a chamber therein, said chamber being closed at one end by a base and having a transverse member at its opposite end provided with a reduced outwardly extending tubular portion, said tubular portion having means for detachably connecting the device to a fluid container, a longitudinally disposed partition in said chamber separating the same into a receiving compartment and a measuring compartment, said partition engaging centrally the transverse member and the opposed sides of the body, said partition terminating short of the base to form a passage communicating said compartments with each other, and an overflow member in said measuring compartment having a longitudinal opening communicating at one end with

said tubular portion and at its opposite end with the measuring chamber at a point short of the end of the partition, said device when communicatively connected to a fluid container being reversible so as to discharge a portion of the fluid into the measuring chamber and when returned to its upright position returning the fluid in the receptacle through the receiving chamber and the overflow member to the container while retaining a predetermined quantity in the measuring chamber.

3. A fluid measuring receptacle of the class described including a body having a chamber therein, said chamber being closed at one end by a base and having a transverse member at its opposite end provided with a reduced outwardly extending tubular portion, said tubular portion having means for detachably connecting the receptacle to a fluid container, a longitudinally disposed partition in said chamber separating the same into a receiving compartment and a measuring compartment, said partition terminating short of the base to form a passage communicating said compartments with each other, and an overflow member in said measuring compartment and connected to said partition, said overflow member having a longitudinal opening communicating at one end with said tubular portion and at its opposite end with the measuring chamber at a point short of the end of the partition, said transverse member coacting with said tubular portion to form a relatively large opening communicating the receiving chamber with the tubular portion, said transverse member also coacting with the overflow member to return excess quantities of the fluid to the container, said receptacle when communicatively connected to an upright fluid container being reversible to discharge a portion of the fluid into the measuring chamber and when the container is returned to its upright position the fluid in the receiving chamber and above the overflow member being returned through the tubular portion to the container while the fluid in the measuring chamber below the overflow member is retained therein so as to be removed therefrom when the receptacle is disconnected from the container.

4. A fluid measuring receptacle of the class described including a body having a chamber therein, said chamber being closed at one end and having a transverse member at its opposite end provided with an outwardly extending tubular portion, said tubular portion having means for detachably connecting the device to a fluid container, a partition in said chamber separating the same into a receiving compartment and a measuring compartment, said partition engaging the transverse member and the opposed sides of the body, said partition being spaced from the closed end of the body to form a passage communicating said compartments with each other, and an overflow member in said measuring compartment having a longitudinal opening communicating at one end with said tubular portion and at its opposite end with the measuring chamber, said device when communicatively connected to a fluid container being reversible so as to discharge a portion of the fluid into the measuring chamber and when returned to its upright position returning the fluid in the receptacle through the receiving chamber and the overflow member to the container while retaining a predetermined quantity in the measuring chamber.

JOHN T. ARNOLD.
